HOLLON C. SPAULDING, OF COLEBROOK, CONNECTICUT.

GEARING.

1,187,669.

Specification of Letters Patent. Patented June 20, 1916.

Application filed May 16, 1912. Serial No. 697,683.

To all whom it may concern:

Be it known that I, HOLLON C. SPAULDING, a citizen of the United States, residing at Colebrook, county of Litchfield, and 5 State of Connecticut, have invented certain new and useful Improvements in Gearing, of which the following is a full, clear, and exact description.

My invention relates to hoisting apparatus 10 and has special reference to that class of hoists which are operated by hand power and are employed for lifting heavy articles.

In the development of hand hoisting apparatus the most satisfactory device so far 15 produced is the "spur geared" chain block, with a planetary or balanced gear train. In this class of apparatus it is necessary to make the initial pinion smaller than is desirable or else sacrifice compactness and head 20 room to obtain the necessary strength.

In my invention, instead of driving the initial pinion of the planetary gear train direct from the hand wheel chain sheave, I 25 interpose a "differential" between them. This reduces the speed of the pinion 50% at the outset, allowing the pinion to be made larger with practically no increase of size 30 of the hoist. A greater gear reduction is also possible with this device.

35 In my invention the load sheave is suspended direct from the hook yoke by suspension pieces in such a way that the supporting mechanism may be allowed to revolve around a common center with the loaded sheave. This allows the interposition of a spring or buffer to take up the shock of the sudden load, and contact pieces may be used to close an electric circuit or in some way give notice that the hoist is loaded to 40 its capacity. Also a simple indicating means may be used which is dependent upon the angular rotation and will give the weight of the load.

45 Other features of my invention are the use of the cam detent instead of the pawl and ratchet for sustaining the load. This makes the device noiseless and also prevents the weight from dropping part way as is the case when a ratchet is used.

50 Other features are the improved chain guide which "fairs" the chain onto the sheave, and the fibrous friction disk.

I have fully and clearly illustrated a preferred form of my invention in the accompanying drawings to be taken as a part of this specification and wherein,

Figure 1 shows a sectional view of the device. Fig. 2 shows a detail view of the clutch mechanism. Fig. 3 shows a detail view of the sustaining strap showing the 60 buffer. Fig. 4 shows the chain guide for the hand wheel, and an end view of the hoist. Fig. 5 shows a sectional view of the chain guide and a portion of the rim of the hand 65 wheel.

Referring to the drawings, 10 is the main shaft of the device. Upon this shaft, by means of a key 11 is fastened the short worm hub 12. The threads 14 of this worm 70

15 is the hand wheel or driving sheave having its periphery grooved as shown at 16 to receive the links of a chain. The hub 17 of this hand wheel sheave is provided with a worm thread 18 which screws over 75 the threads 14 of the worm hub 12. Fasted upon the end of the shaft 10, by the cap bolt is a cap plate 19. This cap plate 80 prevents the worm 17 of the hand wheel driving sheave from coming completely off the hub 12. The plate 19 is however at a short distance from the end of the worm 12 so that a slight unscrewing of the hand 85 wheel may take place before the hub 17 contacts with the plate 12. The purpose of this will be explained later.

Revolutely mounted on the hub 17 is a sleeve 58. This sleeve has two arms 59 and 60 which are extended to the periphery of the hand wheel sheave. Here they are bent 90 in substantially U-shape (see Fig. 5). The U-shape portion of the arms carries studs 62 on which grooved idler wheels 63 are rotatably mounted. These idler wheels are facing and adjacent the grooves and pockets in the periphery of the hand wheel sheave so that not only will the position of the arms automatically accord with the angle of pull 95 in the plane of the hand wheel, but the arm guide wheels 63 being complementary in shape to the grooves in the hand wheel, the chain will be automatically alined and "faired" in feeding into the latter with a minimum of friction. Suitable stops, not shown, are placed on the frame limiting the 100 extreme movement of the chain arm guides.

The clutch devices consist of the friction plate 21, mounted on the shaft 10, but not fastened thereto. This plate has inserted in it the friction plugs 22 (see Fig. 2). 110 These may be of any fibrous material, such as cork. The periphery of this plate 21 is

notched, forming cam spaces, as shown in 23, Fig. 2. These cam spaces slope gradually from the periphery and terminate in an abrupt shoulder 24. In the rear of the 5 friction plate 21 and upon the shaft 10 is a disk 25. This disk extends outwardly and has at its periphery a projecting rim 26 which extends over the periphery of the plate 21.

10 In the cam spaces 23, between the projecting rim 26 and the plate 21 are placed rollers or balls 27. Springs may be provided, bearing upon the shoulder 24 and the balls or rollers but these are not essential to 15 the operation of the device.

Revolubly mounted upon the shaft 10 is the main load sheave 29. This sheave has its periphery formed to engage the links of a chain which has at its end the usual lifting hook. Upon each end of the load sheave 20 are the two load sheave bushings 30. These bushings 30 are formed with a slot 31 adapted to receive the straps 32 and 33. These straps extend upwardly and are fastened to 25 the upper hook yoke 34. The hook 35 is fastened in any suitable manner to this yoke 34.

The sleeve 25 has projecting from it two stops 64 and 65 (see Fig. 3). These stops 30 coöperating with the strap 32 serve to limit the extreme movement of the sleeve 25. To cushion the shock when the load is applied a spring 66 may be used. This spring is attached to the sleeve 25 and to the strap 32 35 so that as the load is put on it comes under tension.

A spring contact piece 67 is fastened to and insulated from the sleeve 25 by a suitable screw. When the maximum load is 40 upon the hoist this spring contact piece will contact with the stop 64, thus closing an electric circuit and notifying the operator by a suitable alarm device that the maximum load is upon the hoist. In lieu of the 45 electrical alarm system a pointer may be attached to the strap 32, this pointer 68, moving over a calibrated scale 69 on the sleeve 25, and so showing the approximate load on the hoist.

50 Fastened to the straps 32 and 33 at the points 37 and 38, respectively, is a load chain guide 39. This guide 39 is grooved to receive the upper part of the load chain and serves as a guide for the chain as well as a brace for the two straps 32 and 33.

The shaft 10 is made larger in diameter at the part where it extends through the load sheave 29. This serves to form shoulders on the shaft 10. The shoulder 40 55 serves as an abutment for the sleeve 25.

Fastened to the extreme right of the shaft by means of a key is a bevel gear 41. Mounted upon the main load sheave 29 adjacent the load bushings 30 is a frame 60 65 42. This frame 42 is fastened to the

strap 33 at 43 and has at its outer periphery the bevel gear teeth 44. These teeth are similar to the teeth 45 of bevel gear 41. Between the frame 42 and the bevel gear 41 revolubly mounted upon 70 the shaft 10 is a spider frame 46. This spider frame carries at suitable points on its periphery the studs 47 which carry the floating bevel gears 48. It can be seen that the gears 41 and 42 form the elements of a 75 differential which is completed by the floaters 48 which are mounted upon and revolve in their orbit with the spider frame 46. The spider frame 46 has an extended hub 49 which has cut in it the spur gear teeth 50. 80

On an extension of the main driving sheave 29 is keyed a cage 51. This cage carries the studs 52, which carry upon them pinions 54 and 55. These pinions are of slightly different diameter. The pinions 54 85 and 55 are fastened together or are made in one piece as desired. Upon a projecting rim 56 of the frame 42 is cut an internal gear 57. The teeth of this gear mesh with the teeth of the pinion 55 and the teeth of the pinions 54 mesh with the teeth 50 of the hub 49. It is therefore seen that the pinion 50 and the gears 54 and 55 together with the internal gear formed on the rim 56 of the frame 42 complete the elements of a 90 sun and planet gearing train. 50 is the sun gear and 54 and 55 the planetary gears.

The operation of the device is as follows:—Upon a clockwise pull of the hand chain the driving sheave runs up the worm 100 14 until it contacts with the friction plugs 22 in the plate 21. The plate and driving sheave then rotate as one. Further movement transversely is prevented by the sleeve 25 abutting against the shoulders 40 of the shaft. The hand wheel driving sheave, the worm hub 14 and the shaft 10 then rotate as one. The shaft 10 rotates the bevel gear 41 and by means of the differential action of the parts 41, 42 and 46 a reduction of 50% is obtained. In other words, 105 the frame 46 rotates at one half the speed of the bevel gear 41.

The power is transmitted from the sun gear 50 to the two planetary gears 54 and 55. 54 meshing with the teeth on the internal gear is prevented from idly rotating and is caused to travel around the shaft 10 and the sun gear 50 in a planetary manner. The gear traveling in this manner carries the 115 stud 52 with it. The stud being rigidly attached to the main load sheave 29 rotates the sheave. Thus it is seen that there is a first reduction in the differential gearing, a second reduction between the sun gear and the planetary gear and a third reduction between the planetary gear and the internal gear. Thus it is seen that a greater gear reduction may be obtained with little or no increase in the size of the hoist. The actual 120 125 130

ratio of chain speed to hoisting speed is dependent upon the proportions of the gears. On releasing the hand chain, the load of course tends to turn the disk 21 in the opposite direction, but the balls or rolls in the cam spaces in its periphery immediately engage with the rim of the sleeve 26 to prevent all but the most incipient rotation, which owing to the plurality of balls or 10 rollers is practically *nil*.

To lower the load the hand chain is pulled in a counterclockwise direction. This counterclockwise movement of the driving sheave 15 tends to run it off the worm 14, 15 and release the friction between 15 and the friction plate 21, upon which the weight of the load acting through the gear train immediately causes a corresponding rotation in the shaft 10, which therefore overhauls 15, 20 and again restores equilibrium through the holding of the friction disk 21. Successive pulls on the hand chain causes similar successive "overhauling" movements on the part of the main shaft 10, so that an infinity of successive "lowering" steps, will 25 render the action practically continuous and the load is lowered smoothly without jar.

What I claim is:

1. In a hoisting device, in combination, a 30 spider having a hub portion, bevel idler gears revoluble on said spider, bevel gears at each side of the aforesaid idler gears and meshing therewith, said bevel gears, spider and idler gearing comprising a differential gear train whereby speed is reduced, gear teeth on the hub portion of the said idler forming a sun gear and planetary gears located between the aforesaid bevel gears and below said bevel idler gears, said planetary 35

gears coöperating with the aforesaid sun 40 gear and teeth on one of the aforesaid bevel gears whereby speed is further reduced.

2. A gear train for hoisting devices, comprising, in combination, bevel gears, one of said gears having internal gear teeth thereon, a spider, idler gears carried by the spider, said bevel gears, spider and idlers coöperating to form a differential gearing to reduce speed; the said spider having external gear teeth thereon forming a sun gear 50 and planetary gears coöperating with the sun gear and the internal gear teeth on the bevel gear, whereby a further reduction in speed is obtained.

3. In a device of the class described, in combination, a differential gearing comprising a stationary gear, having internal gear teeth thereon, a spider having idlers thereon and coöperating with the stationary gear, a second gear in mesh with the said idlers, a 60 planetary gearing comprising planet gears meshing with the internal gear teeth on the aforesaid stationary gear, a spider carrying said planet gears and connected with the member to be driven, a second set of planet 65 gears carried by the said spider and rotating in unison with the first mentioned set of planet gears, and a sun gear driving the second mentioned planet gears, said sun gear being secured to the spider carrying the idlers for the differential gearing.

In testimony whereof I affix my signature in the presence of two subscribing witnesses.

HOLLON C. SPAULDING.
